UNITED STATES PATENT OFFICE.

FRANCIS D. WEEKS, OF SALIDA, COLORADO.

MEASURED-DELIVERY APPARATUS.

1,103,333.

Specification of Letters Patent. Patented July 14, 1914.

Application filed March 2, 1911. Serial No. 611,794.

To all whom it may concern:

Be it known that I, FRANCIS D. WEEKS, a citizen of the United States, residing at Salida, county of Chaffee, State of Colorado, have invented certain new and useful Improvements in Measured-Delivery Apparatus; and I do hereby declare the following to be a full, clear, and exact description of the invention, such as will enable others skilled 10 in the art to which it appertains to make and use the same.

The invention relates to an automatic measuring device by which ore or similar material in bulk may be intermittently transferred in predetermined quantities from a hopper or other receptacle to another location, or in which different materials may be so transferred in predetermined proportions from a plurality of such receptacles or in 20 which a definite rate of feeding may be automatically and continuously maintained from one or more of such receptacles. In some devices of this kind heretofore employed, the quantity of material transferred 25 could not be altered in fine gradations so that the mixtures thereof could not be properly compounded, and processes requiring certain rates of feeding could not be properly carried out automatically and continuously; in others the alteration was secured by 30 adjusting a gate opening and when such opening was small if became clogged by the material transferred.

In accordance with my invention, an endless belt is moved intermittently in one direction through a finely adjustable range beneath a receptacle containing ore or other material in bulk. Each movement of the belt takes a predetermined quantity of material 35 from the receptacle and transfers it to another receptacle or onto a traveling conveyer. By providing a plurality of receptacles containing different materials and a plurality of transmitting devices, the resulting mixture in the common receptacle may 45 be compounded in any desired proportion. Or the material or materials may be fed automatically and continuously at a definite rate by adjusting the bulk transferred from 50 each receptacle at each movement.

In the accompanying drawing forming a part of this specification, Figure 1 is a front elevation of a plurality of receptacles and transmitting devices and a traveling conveyer arranged to transfer the discharge

from all of the receptacles into a common receptacle. Fig. 2 is a transverse vertical section of a receptacle containing material in bulk, showing a transmitting device and a conveyer, wherein the belt of the transmitting device forms the bottom of the receptacle. Fig. 3 is a side view showing the detailed construction of the transmitting device and means for indicating the adjustment. Fig. 4 is a plan view, partly in section, and illustrates the driving end of a transmitting device which discharges directly into a fixed receptacle. Fig. 5 is a vertical section of a modification in which the transmitting belt does not form the bottom of the receptacle.

The receptacle 1 is an ordinary hopper, having some or all of its sides sloping toward the bottom, in order to aid the downward movement of the material 2 to be fed. The bottom of the receptacle may be formed by the endless belt 3 of the transmitting device, as illustrated in Fig. 2, or the bottom may be a part of the receptacle 1 as shown in Fig. 5. The belt may, if desired, be held 80 in close proximity to the bottom of the receptacle by a roller bed or otherwise, as shown in Fig. 2. There is an opening 4 in the front side of the receptacle, which may be adjusted in height by means of the sliding gate 5. The bolt 6 in the slot 7 secures the gate in any desired position.

In the transmitting device herein illustrated, the rotatable shaft 8 for producing the intermittent motion is supported from 90 the receptacles by means of the brackets 9. There is provided for each receptacle an eccentric 10 rigidly mounted on the shaft 8. The rod 12 is secured at one end to the collar 11 which incloses the eccentric, while the other end is loosely held by the turnbuckle 13. The other end of the turnbuckle is screwed onto a rod 14, which is attached to the lever 17 by means of a slotted link 15 and the pin 16. The framework 18 of the 100 transmitting device supports the bearings 19 through which extends the driving shaft 20 and the braking shaft 21. At one end of the driving shaft is rigidly mounted the driving pulley 22 while loosely mounted thereon is 105 the pivoted lever-frame 17. The driving strap 23 extends partly around the driving pulley and has a weight 24 attached to one end, while the other end is connected to the pivoted lever-frame. The brake strap 25 ex- 110

tends partly around the brake pulley 26. It has the weight 27 attached to one end, while the other end is immovably fastened by means of the connection shown at 28. The 5 driving shaft rigidly carries another pulley 29 and the braking shaft similarly carries the pulley 30. The endless belt 3 extends around these two pulleys and passes in close proximity to the bottom of the receptacle, 10 forming the bottom thereof if desired. The extreme movement of the lever-frame 17 is limited in one direction by a stop 31 projecting from the frame-work 18 and engaging the inner arm of the frame. 15 The endless belt of the transmitting device or devices may discharge the material or materials into a fixed receptacle 32, as shown in Fig. 4, or the materials may be discharged into a traveling conveyer 33, of 20 the ordinary construction, and thence into a common receptacle 34, as shown in Fig. 1. The vertical plates 35 direct the discharge of the material from the endless belt to the conveyer. 25 The operation of the automatic measuring device will now be described. In the construction shown, the primary driving shaft 8 is rotatable and its rotary motion is converted by the eccentric 10 into a reciprocating motion of the connecting members 12, 13 and 14. By means of the adjustable connection at 15 and 16, such reciprocating motion is converted into a minutely adjustable oscillation of the pivoted lever-frame 30 17 to which the strap 23 is connected. The upward movement of that end of lever-frame 17 on which strap 23 is connected is limited by the stop 31, and its downward movement is determined by the adjustment 35 of the turnbuckle. During such downward movement the strap 23 is held in frictional engagement with the pulley 22 by the weight 24 and a counterclockwise movement of the pulley, as viewed in Fig. 3, results, which 40 imparts a corresponding movement to the feed belt 3 and the bed of ore or other material carried thereby. This movement of belt 3 imparts a corresponding movement to shaft 21 and brake pulley 26. The tendency 45 of this movement of the brake pulley is to lift the weight 27 and release the frictional engagement of the strap 25 with the pulley. This lifting of the weight is very slight, only sufficient to slack the strap 25, but it 50 is sufficient to permit the rotation of pulley 22 under the impulse of strap 23 and the forward movement of the feed belt. As the rod 12 begins to descend the connected end of lever-frame 17 falls and the end of the 55 strap connected to the other end of the lever-frame rises, under the pull of weight 24, but now the brake strap 25 is stretched tight on pulley 26 and exerts sufficient braking effect thereon to prevent the reverse 60 movement of pulley 22, and the friction 65

driving strap 23 slips over that pulley. The extent of the linear movement of the endless belt may be altered by adjusting the turnbuckle, since the instant at which the slotted link engages the pin in the upward 70 travel of the vertical arm depends upon this adjustment. If the slotted link is raised by the turnbuckle, the link engages the pin 16 at an earlier point in the cycle of rotation of the shaft 8, and thereby advances the 75 start of the movement of the endless belt. Similarly, if the slotted link is lowered by the turnbuckle, the point of the cycle of rotation of the shaft at which the link engages the pin is delayed. In this way, the 80 start of movement of the endless belt relatively to the start of the cycle may be varied gradually throughout a wide range. The pivoted lever-frame 17 carries an arm or pointer 36 which sweeps over a graduated 85 scale 37 during the oscillatory travel of the lever. In this way, a measure of the angular movement of the pivoted lever is indicated on the graduated scale, thereby indicating the extent of the linear movement of the 90 endless belt during each cycle. I may graduate this scale in angular measure or in terms of length or of volume corresponding to a certain gate opening, to indicate the amount of material transferred from the 95 receptacle during each cycle. Furthermore, the movement of the endless belt may be started and ended at different points of the cycle of rotation of the shaft by adjusting the eccentric on the shaft. In this way, the 100 start and end of the movement of a plurality of transmitting devices actuated from a common shaft and having the same turnbuckle adjustment may be altered; and by also adjusting the turnbuckle, both the start and 105 ends of the movements during each cycle of rotation of the common shaft may be altered at will.

In order to provide means for automatically compounding materials in predetermined proportions in a common receptacle, I employ a plurality of receptacles, each containing different material and each having a separate transmitting device of the character described. These transmitting devices may discharge the material directly into a common receptacle, or they may discharge onto a traveling conveyer, which empties into another receptacle. The amount of material discharged by each 110 transmitting device may be adjusted to any predetermined amount in two different ways. The extent of movement of the transmitting device may be altered by adjusting the turnbuckle, or the sliding gate may be 115 adjusted in position. In the first case, the length along the transmitting belt of the material transferred during each cycle is altered, and in the second case its thickness is altered. It is also obvious that adjust- 120 125 130

ment of the amount of material transferred may also be secured by combining these means. Since all of the transmitting devices are actuated by a common shaft, the frequency of the cycles is the same for all. Therefore by adjusting the amount of material transferred during each cycle, the total material discharged into the common receptacle is compounded in the same proportions. If the speed of rotation of the common shaft is altered, the frequency of the movements of all the transmitting devices will be altered in accordance therewith, but the compound will always have the same proportions. It is also evident that the direction of movement of the endless belt is independent of the direction of rotation of the eccentric. When the transmitting devices discharge the material onto a traveling conveyer, the speed of the conveyer or the positions of the eccentrics may be so adjusted that the materials are not superposed. In this way the volume of material per unit length of conveyer is constant, if the gate openings are equal, since the speed of all the transmitting devices is the same. Furthermore, by properly adjusting the gate openings, the weight of material per unit length of conveyer may be made constant. If I desire to use my device for feeding at a constant rate, I adjust the turnbuckle, and the gate opening if desired, so as to secure the proper amount of discharge during each cycle. Then, I may adjust the speed of rotation of the driving shaft to provide the proper frequency of such cycles. If the feed is to consist of one kind of material, I may utilize but one of the receptacles, or I may utilize more of the receptacles in order to increase the rate of feed. However, if the feed is to consist of different materials, I utilize a number of receptacles, corresponding to the number of constituents, and adjust each transmitting device in accordance with the required proportions.

From the foregoing description of a typical embodiment of my invention, it will be seen that I provide mechanism for converting the continuous rotary or reciprocating movement of a primary driving mechanism into a minutely adjustable intermittent advance movement of the feed belt by interposing between the primary driving mechanism and the feed belt co-acting driving and driven friction members connected respectively to the primary driving mechanism and to the feed belt, the connections from the primary driving mechanism to the driving friction member including mechanism for converting the primary driving motion into an oscillation of the driving friction member, and the driven friction member being arranged to move with the driving friction member in one direction and not in the other. Many different forms of friction members may be substituted for the strap and pulley shown and the brake strap and pulley may be replaced by any suitable means for preventing the reverse movement of the pulley 22. Furthermore, and for the purpose of supplying an accurate mixture of several different materials, I have arranged the several bins with their independently finely adjustable feeding devices driven from a common source, whereby the different mechanisms being set to feed in proper proportions, the feed will continue at any desired rate, but always in the same proportions until a different adjustment is made. By means of this exact and widely variable adjustment of the extent of movement of the belts, there may be provided sufficient latitude of alteration of feed, and sufficiently exact control, for all ordinary purposes, without providing adjustable gate-openings for the bins, and indeed for such ordinary purposes I prefer to fix once for all big free openings at the mouths of the bins, thereby avoiding the faults which are inherent in any attempt to control the feed by adjusting a gate-opening. Nevertheless, in special cases the well known adjustable gate-openings may be employed, as described above.

What I claim is:

1. In an automatic measured-delivery apparatus, a receptacle, a feed belt upon which the receptacle discharges, and mechanism for intermittently moving said belt including co-acting driving and driven friction members, mechanism for oscillating the driving friction member, means independent of the primary driving mechanism for imparting to the driving friction member a limited pressure of engagement during the advance movement and mechanism for preventing the reverse movement of the driven friction member by the driving friction member. 95
2. In an automatic measured-delivery apparatus, a receptacle, a feed belt upon which the receptacle discharges, and mechanism for intermittently moving said belt including co-acting driving and driven friction members, adjustable mechanism for oscillating the driving friction member through 100 an angle variable at will, means independent of the primary driving mechanism for imparting to the driving friction member a limited pressure of engagement during the advance movement and mechanism for preventing the reverse movement of the driven friction member by the driving friction member. 105
3. In an automatic measured-delivery apparatus, a plurality of bins, an individual carrying belt for each bin and upon which it discharges, and mechanism comprising a friction drive for intermittently advancing said belts and including means for independently adjusting the extent and timing 115 120 125 130

- of the advance movement of each belt, and means for collectively adjusting the frequency of the advance movements.
4. In an automatic measured-delivery apparatus, a plurality of bins, an individual feed belt for each bin and upon which it discharges, each bin having an adjustable feed orifice, and mechanism for intermittently advancing said belts including means for independently adjusting the extent and timing of the advance movement of each belt and means for collectively adjusting the frequency of the advance movements.
5. In an automatic measured-delivery apparatus, a plurality of bins, an individual feed belt for each bin and upon which it discharges, mechanism for intermittently advancing said belts including means for independently adjusting the extent of the advance movement of each belt, and an indicator associated with each belt for showing the extent of the advance movement thereof.
6. In an automatic measured-delivery apparatus, a plurality of bins arranged side by side, a rotatable driving shaft extending along said bins, an individual feed belt for each bin and upon which it discharges, and mechanism for converting the continuous rotary motion of the driving shaft into intermittent advance movements of the individual belts, said mechanism comprising for each belt, a pivoted lever, an adjustable connection between the pivoted lever and the driving shaft, a pulley arranged to drive the feed belt, a tensioned friction strap in engagement with the pulley and connected to the free end of said pivoted lever, and mechanism for preventing the backward movement of the feed belt.
7. In an automatic measured-delivery apparatus, a plurality of bins arranged side by side, a rotatable driving shaft extending along said bins, an individual feed belt for each bin and upon which it discharges, and mechanism for converting the continuous rotary motion of the driving shaft into intermittent advance movements of the individual belts, said mechanism comprising for each belt, a pivoted lever, an adjustable connection between the pivoted lever and the driving shaft, a pulley arranged to drive the feed belt, a tensioned friction strap in engagement with the pulley and connected to the free end of said pivoted lever, and mechanism for preventing the backward movement of the feed belt.
8. In an automatic measured-delivery apparatus, a plurality of bins arranged side by side, a rotatable driving shaft extending along said bins, an individual feed belt for each bin and upon which it discharges, and mechanism for converting the continuous rotary motion of the driving shaft into intermittent advance movements of the individual belts, said mechanism comprising for each belt, co-acting driving and driven friction members, mechanism for oscillating the driving friction member, means independent of the primary driving mechanism for imparting to the driving friction member a limited pressure of engagement during the advance movement, and mechanism for preventing the reverse movement of the driven friction member by the driving friction member.
9. In an automatic measured-delivery apparatus, a plurality of bins arranged side by side, a rotatable driving shaft extending along said bins, an individual feed belt for each bin and upon which it discharges, and mechanism for converting the continuous rotary motion of the driving shaft into intermittent advance movements of the individual belts, said mechanism comprising for each belt, co-acting driving and driven friction members, adjustable mechanism for oscillating the driving friction member, means independent of the primary driving mechanism for imparting to the driving friction member a limited pressure of engagement during the advance movement of the driven friction member by the driving friction member.
- In testimony whereof I affix my signature, in presence of two witnesses.
